UNITED STATES PATENT OFFICE

ELLIS HARTLEY, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

DOLL-ROLL TWISTER STOP MOTION

Application filed November 11, 1929. Serial No. 406,274.

This invention relates to improvements in a stop motion for a twister of the so-called "doll roll" type. In such twisters the more usual horizontal feed rolls are replaced by single doll rolls, rotatable on vertical axes and around which the yarn is fed in a helical path.

It is the object of my invention to provide improved means for stopping any one of the doll rolls upon breakage of the yarn fed therefrom, and to provide means for preventing rebound of the doll roll when the rotation thereof is thus stopped.

My invention further relates to arrangements and combinations of parts which will be hereinafter described and more particularly pointed out in the appended claims.

A preferred form of the invention is shown in the drawings in which

Fig. 1 is a partial sectional side elevation of parts of a twister embodying my improvements;

Fig. 2 is an enlarged sectional side elevation of the doll roll and stopping mechanism;

Fig. 3 is a side elevation of a portion of the driving mechanism, looking in the direction of the arrow 3 in Fig. 2, and

Fig. 4 is a sectional plan view of certain parts, looking in the direction of the arrow 4 in Fig. 2.

Referring to the drawings, I have shown a portion of a twister frame 10 having the usual spindles S mounted on a spindle rail 12 and supporting spools or bobbins B, rotatable in rings 13 mounted on a ring rail 14. Yarn spools 20 are loosely mounted on creel rods 22 and supply yarn strands Y from which the thread T is twisted.

A doll roll 25 is provided for each spindle S and each doll roll is mounted on a fixed stud 27 (Fig. 2) secured in a frame member 28.

A driving member 30 is loosely mounted on each stud 27 and has a worm and worm wheel or spiral gear connection with a driving shaft 32, by which all of the members 30 are continuously rotated. A plate 34 is loosely mounted on each stud 27 and above the driving member 30 and supports a pawl 35, pivoted at 36 on said plate and having a

hook-shaped portion adapted to be engaged by a driving arm 38 on the driving member 30.

The doll roll 25 has a depending sleeve or hub portion 40, provided with a projecting lug 41 adapted to be received in a slot in the upper portion of the driving plate 34. The doll roll thus has a detachable driving connection with the plate 34.

The yarn strands Y pass from the spools 20 through a guide eye 50, around the doll roll 25, through a second guide eye 51, under a guide rod 52, and through an eye 53 in the end of a two-piece stopping lever 55. The thread T then passes under a traveler 56 on the ring 13 and thence to the bobbin B.

The lever 55 is pivoted at 60 on a bracket 61 secured to a cross frame member, and the rear or inner end of the lever 55 is provided with a forked end having offset lugs 62 (Fig. 70 4) which may be positioned for engagement with the upwardly extending end portion of the pawl 35 as the plate 34 is rotated.

During normal operation, the lever 55 is held in the position indicated in Fig. 1, with its outer portion resting on a stop lug 63, the lever being held in this position by the downward pull of the thread T. If the thread T is broken, the forked inner portion of the lever 55 over-balances the outer portion and the lever moves to the position indicated in Fig. 2, with the lugs 62 in the path of the pawl 35. Further rotation of the plate 34 causes the pawl 35 to be engaged by one or the other of the lugs 62 and to be raised to the inoperative position indicated in Fig. 2, thus stopping the rotation of the doll roll 25.

It has been found in high speed operation that this abrupt stopping of the doll roll 90 frequently causes a rebound thereof sufficient to lower the hook-shaped end of the pawl 35 again into the path of one of the driving arms 38, very often resulting in breakage of the pawl or the driving arm.

To prevent such rebound and re-engagement, I have provided a lug or abutment 70 on the upper surface of the plate 34, so positioned that it will engage one face of the offset lug 62 whenever the doll roll is stopped 100.

by engagement of the opposite face of the lug 62 with the pawl 35.

Such engagement of the lug 70 with the lug 62 prevents reverse motion or rebound of the doll roll, and consequently prevents re-engagement of the pawl 35 and consequent breakage thereof.

A twister equipped with the stop motion herein described is capable of high-speed operation and any individual doll roll may be effectively brought to rest upon thread breakage and will be thereafter held from reverse rotation.

Having thus described my invention and the advantages thereof, I do not wish to be limited to the details herein disclosed but what I claim is:—

1. In a twister, a doll roll, driving means therefor including a driving arm and a clutch pawl, a yarn-controlled lever effective on yarn breakage to disengage said clutch pawl from said driving arm, and means to prevent rebound of said doll roll when forward rotation thereof is stopped by said lever.

2. In a twister, a doll roll, driving means therefor including a driving arm and a clutch pawl, a plate rotatable with said doll roll and on which said pawl is pivotally mounted, a yarn-controlled lever effective on yarn breakage to engage said pawl and to disconnect said pawl from said driving arm, and a lug or said plate positioned to thereupon engage said lever and thereby prevent rebound of said doll roll when stopped by said lever.

In testimony whereof I have hereunto affixed my signature.

ELLIS HARTLEY.
